DESIGN FOR A GAME BOARD

Eugene E. Almy, Sherman Oaks, Calif.

Application January 18, 1947, Serial No. 136,249

Term of patent 14 years

(Cl. D34—5)

To all whom it may concern:

Be it known that I, Eugene E. Almy, a citizen of the United States of America and a resident of the city of Sherman Oaks, in the county of Los Angeles and State of California, have invented a new, original, and ornamental Design for Game Board, of which the following is a specification, reference being had to the accompanying drawings, forming part thereof.

In the drawings the figure shows a top perspective view of my new game board design, the rear side thereof being plain and void of any design features.

I claim:

The ornamental design for a game board, substantially as shown and described.

EUGENE E. ALMY.
